COMPOSITION SHOWER PAN

Glenn A. Merthland, Los Angeles, Calif.

Application July 30, 1938, Serial No. 222,190

6 Claims.

(Cl. 72—14)

This invention relates generally to shower pans such as are installed in shower rooms, underneath the tile, to prevent any water which has seeped down through the tile and cement from reaching the sub-flooring, and relates more particularly to the provision of a shower pan of a composition type.

It is common to use for this purpose a pan made of lead. A metal pan, however, is subject to deterioration by electrolysis and by reason of attack by the lime in the cement. Metal pans are also somewhat costly and difficult to install, the installation of such a pan ordinarily requiring several hours labor.

One object of the present invention is to provide a water-proof shower pan which is not subject to the deterioration characteristic of the usually employed lead pan.

A further object of the invention is to provide a permanent, water-proof shower pan of a composition type, which is exceptionally strong against tearing or cutting, which conforms to irregularities which may be present in the bottom and sides of the shower stall, and which is also conformable to the usual cement and tile laid above it, whereby stresses set up in the cement in which the tile is laid may be relieved, and an assembly provided which is in perfect equilibrium as regards internal strain.

The shower pan of the present invention is made up of a composition of layers of flexible material, at least one of which is of a fabric or felted type, preferably water-proofed, and characterized by a certain amount of "give," and at least another of which is a water-proof plastic substance, such as an asphalt plastic, the latter being designed to conform to any unevenness in the cement layer placed in the pan. In some instances, it is desirable to use two layers of the plastic material, separated for example by a layer of asphalt roofing felt. The assembly as thus described is enclosed by cover layers, which may comprise, for the bottom of the pan, a layer of roofing felt, and for the top, a layer or double layer of kraft paper.

The assembly as thus described is entirely safe and water-proof, has adequate strength against tearing or cutting by any uneven surface or edge on which the pan may rest, and is characterized by conformability to the cement and tile placed inside it, whereby stresses and strains in the cement and tile are relieved, and a permanent structure is provided which is not subject to deterioration, tearing, cracking or leaking.

The invention will be better understood by re-

ferring now to the following detailed description of several typical present embodiments thereof, reference for this purpose being had to the accompanying drawing, in which:

Fig. 1 is a vertical longitudinal section through the lower portion of a shower room showing the installation of my improved shower pan;

Fig. 2 is a perspective view showing one form of shower pan in accordance with the present invention, the view demonstrating how the pan may be folded flat for shipment purposes, and unfolded to box form when ready to be installed;

Fig. 3 is a perspective view of a corner of the shower pan of Fig. 2, a portion of the upper cover layer being broken away to expose the manner of folding of the different layers at the corners of the pan;

Fig. 4 is an enlargement of a portion of Fig. 1, being a cross-section through a portion of the shower pan;

Fig. 5 is a plan view of a modified form of shower pan in accordance with the present invention, parts being broken away; and

Fig. 6 is a section on line 6—6 of Fig. 5.

In Fig. 1, numeral 10 designates generally a shower room, of the common stall shower type, the sub-flooring being designated at 11, the studing framing the shower room being indicated at 12, lathing at 13, and the shower pan of the present invention being generally designated by numeral 14. The shower pan is of the usual box form, its bottom 15 resting on flooring 11, and its sides 16 extending upwardly a matter of approximately six inches from bottom 11 adjacent lathing 13. Numeral 17 indicates the usual layer of cement placed over the bottom 15 of the shower pan, and numeral 18 designates the coating of cementitious material placed over lathing 13. The usual tiling is designated by numeral 19. The shower room is shown provided with the usual water drain 20, which extends through a hole in flooring 11 and bottom 15 of shower pan 14. The cement and tile are installed around this drain in the usual manner.

Reference now being directed more particularly to the form of the invention shown in Figs. 2, 3 and 4, the bottom or outside layer 25 of the shower pan serves simply for a suitable bottom cover, and may be composed of any one of various materials. Preferably, however, this bottom layer 25 is formed of a 15 lb. asphalt roofing felt, which is not only strong but has water-proof characteristics. In a later described modification, the asphalt felt is itself covered with a layer or double layer of water-proof paper, such as kraft

paper. If desired, such an outside bottom cover may be placed below layer 25.

Above layer 25 is a layer 26 consisting of a flexible fabric material which is strong against tearing or cutting. A woven fabric such as burlap may be used for this purpose. However, I may employ for this layer a flax felt fabric, known to the trade as Irish flax felt. Either of these materials are exceptionally strong against tearing or cutting, and will give without parting or cutting if the pan should happen to be installed over an uneven surface or sharp edge. For the purpose of the specification and claims, the term fabric is used generically and covers a woven material, such as burlap, as well as a felt type material, such as flax felt.

Fabric layer 26 is water-proofed by thoroughly impregnating it with a suitable preservative and water-proof substance, such as asphalt paint.

Above layer 26 is placed a layer 27 of a water-proof plastic material, such as asphalt plastic or asphalt putty. A material suitable to the purpose is marketed under the trade-name Hydro-seal. This plastic material within the shower pan causes the pan to be conformable to the cement and tile laid in the pan. Though in some instances a single layer of the plastic material may be regarded as sufficient, Fig. 4 shows a preferred form of the invention in which two layers of the plastic material are employed. The upper plastic layer, which will be understood to be of the same nature as the previously described layer 27, is designated at 28, and may be separated from layer 27 by a separation layer 29 of any suitable material, though I preferably use for layer 29 a 15 lb. roofing felt of the same nature as used for bottom layer 25.

Over plastic layer 28 is placed a cover of any suitable material. I preferably use for this purpose a double layer 30 of heavy water-proof brown paper, of the type known to the trade as kraft paper. The paper cover 30 is bent over and around the edge 31 of the assembled layers, being of sufficiently large dimensions to at least overlap marginal portions of bottom layer 25. In a later described form of the invention, this kraft paper covers the entire bottom of the pan. The advantage of such provision is that the roofing felt 25 which otherwise constitutes the bottom layer of the pan is somewhat dirty to handle. It will of course be obvious that, as in the form of Figs. 5 and 6, this kraft paper may, if desired, be used over the entire bottom of the form of pan illustrated in Figs. 2, 3 and 4. The several layers are preferably fastened together by any suitable fastening means, such as the clips indicated by numeral 35 in Figs. 2 and 3. The described overlapping of the kraft paper over the marginal edges of the composite sheet has the very important advantage of enclosing the interior layers and protecting them against loss of the volatile constituents of the asphalt materials between the edges of the layers.

The layers as above described are first assembled in flat form, the outside dimensions being approximately six inches greater all around than the dimensions of the shower room into which the pan is to be installed. The side portions 16 are next bent up and the pan assembled into box form. This is accomplished by folding the various layers at each corner of the pan in the manner indicated in Fig. 3. From inspection of that figure it will be evident that each paper or felted layer is given what is known as either a "box" or a "dog-eared" fold 36, the folds of successive layers

being bent in opposite directions, so as to avoid, as much as possible, bulkiness on either side of the corner. The corner folds having been made in this manner, the paper cover 30 is bent over upper edges 31 and stapled or otherwise secured in assembly with the remaining layers making up the pan.

For packing for shipment purposes, the pan, at this time in box form, may then be folded along lines 37 into a compact flat-folded form.

When the pan is to be installed in the shower room, it is placed on the sub-flooring of the room in its flat-folded condition, after which its sides 16 are bent out. These sides 16 may, if desired, be stapled against the lathing to hold them in place while the cement is being placed. It will of course be understood that prior to placement of the cement layer 17, a hole 39 will be made in the pan for drain 20, and the bottom of the pan 20 will be fitted and sealed around the drain in the usual manner.

The composition pan as thus described has many advantages. It is thoroughly water-proof. The materials of which it is composed are not subject to deterioration, and the installation is therefore permanent. The flexible fabric or flax felt layer 26 is exceptionally tough and strong, being adapted to give without tearing or cutting when placed over uneven surfaces or sharp edges. This layer, which is asphalt-impregnated for water-proofing purposes, thus gives strength and toughness to the bottom of the pan. The plastic layer or layers 27, 28, typically of an asphalt type, such as plastic asphalt and cement, is designed to give the bottom of the pan the characteristic of conformability to the cement layer in the pan. For example, in laying the cement and in setting the tile, certain stresses and strains are produced causing the bottom surface of the cement to be pressed more or less unevenly against the upper surface of the pan. Plastic layers 27 and 28 enable the pan to conform to any such unevenness as may be produced, so that when the cement and tile are finally placed and set, they are uniformly supported at all points by the pan, with all interior stresses and strains eliminated. The assembly is thus in a condition of equilibrium, with tendencies to cracking of the cement and tile due to uneven support by the pan eliminated. The labor of installing the composition pan of the present invention is reduced to a minimum, nothing being required beyond placing the pan in the shower stall, unfolding its side portions 16, and fitting and sealing the bottom around the drain pipe.

Figs. 5 and 6 show a variational form of the invention. The form of the invention shown in Figs. 2, 3 and 4 may be delivered to the job in box-form, that is, in the condition shown in Fig. 2. In the form of Figs. 5 and 6, the pan may be sent out to the job in flat form, being formed into box shape after placement on the floor of the shower stall. This is a feature of particular advantage, enabling the pan to be boxed on the job to meet the precise dimensions of the stall.

With particular reference to Fig. 6, the pan in this instance is shown as made up of a layer 40 of asphalt roofing felt, a layer 41 of asphalt-impregnated fabric or felt, such as flax felt, a single layer 42 of asphalt plastic, and top and bottom cover layers 43 and 44, respectively, which are preferably double thicknesses of water-proof kraft paper. A double layer of the plastic could of course be used, if desired, the same as in Figs. 2 to 4. Paper cover 44 is shown as overlapped over the edge of the pan, as indicated at 44a,

and the assembly is secured together by any suitable fastening means, as by means of staples 45. Preferably, a square of layers 41 and 42 is removed from each corner of the pan, as along lines 46 and 47, in order to avoid bulkiness when the pan is finally folded into box form as it is installed in the shower stall.

It will be understood the drawings are merely illustrative of and not restrictive on the invention, since various changes and modifications in arrangement and in materials employed may be made without departing from the spirit and scope of the appended claims.

I claim:

1. A composite shower pan or the like comprising a layer of asphalted felt, a layer of burlap impregnated with asphalt over said asphalted felt, a layer of plastic asphalt above said burlap, a layer of asphalted felt over said plastic, and a paper cover layer over the last mentioned layer.

2. A composite shower pan or the like comprising a layer of asphalted felt, a layer of a fabric adapted to give somewhat without tearing placed above said asphalted felt, a layer of plastic asphalt adjacent said last mentioned layer, a layer of asphalted felt above said last mentioned layers, and a cover layer of building paper over the last mentioned layer.

3. A composite shower pan or the like comprising upper and lower outside layers of smooth surfaced building paper, and inside waterproofing layers comprising two layers of asphalt felt, two layers of asphalt plastic, and a layer of asphalt impregnated burlap adjacent at least one of said layers of asphalt plastic.

4. A composite shower pan or the like comprising upper and lower outside layers of smooth surfaced building paper, and inside waterproofing layers comprising two layers of asphalt felt, two layers of asphalt plastic, and a layer of asphalt impregnated fabric of a character adapted to give somewhat without tearing.

5. A composite shower pan or the like comprising upper and lower outside layers of smooth surfaced building paper, and inside waterproofing layers comprising two layers of asphalt felt, two layers of asphalt plastic, and a layer of asphalt impregnated fabric of a character adapted to give somewhat without tearing, one of said outside paper layers being folded around the edges of the composite pan so as to overlap the other of the paper layers, in such manner that the inside layers are entirely enclosed and protected against loss of volatile constituents of the asphalt materials between the edges of said layers.

6. A composite shower pan or the like comprising a layer of asphalted felt, a layer of a fabric adapted to give somewhat without tearing placed above said asphalted felt, a layer of plastic asphalt adjacent said last mentioned layer, a layer of asphalted felt above said last mentioned layers, and a cover layer of building paper over the last mentioned layer, said cover layer of building paper being folded around the edges of the composite pan so as to overlap the bottom of the composite sheet, in such manner that the inside layers are entirely enclosed and protected against loss of volatile constituents of the asphalt materials between the edges of said layers.

GLENN A. MORTHLAND.
